TROPHY CUP OR THE LIKE

Jean Mayeur, Forest Hills, N.Y., assignor to Cartier, Inc., New York, N.Y., a corporation of New York

Filed Aug. 7, 1959, Ser. No. 57,095

Term of patent 7 years

(Cl. D29—23)

Fig. 1 is a front elevational view of a trophy cup embodying my new design.

Fig. 2 is a rear elevational view of the same.

Fig. 3 is a side elevational view of the same, both sides of the cup being identical.

Fig. 4 is a top plan view of the cup.

I claim:

The ornamental design for a trophy cup or the like, as shown.
